UNITED STATES PATENT OFFICE

RUSSELL S. WEHLER, OF YORK, PENNSYLVANIA

SCORE CARD

Application filed October 11, 1930. Serial No. 488,114.

This invention relates to a score card and pencil holder for miniature golf players or other games.

An object of the invention is to provide a score card with a plurality of loops formed by slitting the card, one of said loops extending downwardly from the card and providing a loop hole for receiving the second or third finger of the player and the other loop 10 extending upwardly from the score card for forming a loop hole receiving a pencil.

Numerous other objects of the invention will be apparent from a reading of the following description taken in conjunction with 15 the drawings attached hereto and forming a part hereof, in which—

Figure 1 is a side view of the device shown attached to the hand of the user.

Figure 2 is a plan view of the device.

Figure 3 is an edge view of Figure 2. Miniature golf courses ordinarily provide score cards and pencils but it frequently becomes convenient in hot weather to remove one's coat with the result that the score card 25 and pencil must be laid aside during the putting operation which retards the progress of the game and due to the excitement or forgetfulness these score cards are frequently lost and an accurate record of the match is 30 not obtained.

I have discovered that a score card may be suitably formed for insertion over one's second or third finger in such a manner as not to interfere with the putting.

Referring now particularly to the drawings, 1 represents a score card indicating the number of the holes and the parts thereof with blanks for records of the player's score thereon. In carrying out my invention I slit 40 this score card intermediate the top and bottom portions thereof to provide a downwardly extending loop 2. When this loop is pushed away, in a downward direction, from the score card, it defines a loop hole 3 situated in such a manner that either the second or third finger of the player may be inserted within the loop hole and extending transversely of the score card so that, when worn on the left hand, the 45 card is clearly visible when the elbow is bent.

These slits extend only partially the length of the score card leaving the space 4 for the players' names.

For the purpose of providing a convenient holder for the pencil, I slit the score card 55 as at 5 to provide an upwardly extending loop 6 of somewhat greater width than the downwardly extending loop 2. This pencil loop provides a loop hole for the pencil 7 as shown in the drawings. When in position the pencil, as shown, extends transversely of the score card and may be readily withdrawn from the loop hole for making a record of the "eagles", "birdies", or "pars" 60 or other scores. 65

As will be apparent, the score card when in place conforms to the curvature of the hand and does not in any sense interfere with the putting skill of the player.

Having thus described my invention what 70 I claim is:

1. A score card of the character described, comprising a loop portion provided by slitting the score card intermediate its ends for the insertion of a finger of the operator and a 75 second loop portion, extending upwardly from the score card, for receiving a pencil.

2. A score card adapted to be attached to a finger of a player and being slitted intermediate its top and bottom edges to provide 80 a downwardly extending loop for receiving the finger of the operator, a second loop positioned above the first mentioned loop and extending outwardly from the score card to provide a holding means for the pencil. 85

3. A miniature golf score card having slits extending vertically therein to provide a loop positioned intermediate the side portions of the score card, said score card having indicia of the holes and record receiving portions for 90 the holes played thereon on each side of said loop, said loop being adapted to be extended downwardly from the score card for receiving the finger of the operator whereby the score card is placed to a curvature substantially corresponding to the upper portion of the hand, and means for detachably 95 securing a pencil along a marginal edge of said score card.

4. A score card of the character described, 100

comprising a loop formed by slitting the score card substantially centrally thereof, said score card having indicia and spaces for records on each side of the centrally disposed loop, said loop being adapted to receive a finger of the player inserted transversely therein, a second loop of greater width than the first named loop situated at the top portion of the score card and extending outwardly therefrom for receiving a pencil.

10 In testimony whereof I affix my signature.
RUSSELL S. WEHLER.
